ANTISURGE CONTROL FOR REFRIGERATION COMPRESSORS

Arnold H. Heineman, Chicago, Ill., assignor, by
mesne assignments, to Guardite Corporation,
Wilmington, Del., a Delaware corporation

Application March 11, 1947, Serial No. 733,799

4 Claims. (Cl. 230—22)

1

This invention relates to a surge control for centrifugal compressors, and more particularly to a means for automatically preventing surging.

Centrifugal pumps are commonly used for refrigeration compressors, and the like. In the operation of such compressors, the compression ratio, that is, discharge pressure divided by the suction pressure, often reaches such magnitude as to cause the gases undergoing compression to surge back over the blades of the compressor from the discharge side to the suction side of the pump. Such surging causes considerable noise, vibration and materially detracts from the efficient operation of the machine.

I have invented, and am herein disclosing and claiming a control for centrifugal compressors which will automatically prevent surging by maintaining the compression ratio within predetermined limits. By use of my device, the compression ratio will never exceed a predetermined maximum and the device is operative regardless of discharge or suction pressure, being responsive only to compression ratio.

The invention will be described in conjunction with the drawings, in which Fig. 1 is a schematic drawing of the device; and Figs. 2 and 3 are enlarged detailed views of the control means shown in Fig. 1.

Referring now to the drawing, 10 indicates a centrifugal compressor having a discharge conduit 11 and an intake or suction conduit 12. Bypass means 13 are provided between the discharge and the suction side of the compressor, the bypass being normally closed by valve means 14. Connected to the discharge side of the compressor by means of a conduit 15 is a regulating means 16. A supply of regulating fluid under pressure (preferably compressed air) is connected to the regulating means by a conduit 17. The regulating means 16 may be of any ordinary type capable of preventing flow from the conduit 17 into the conduit 18, but responsive to the pressures in the conduit 15 to permit such flow. As shown in Fig. 2, a valve 40 is mounted on a valve stem 41 which is connected to a diaphragm 42 enclosed in a housing 43. The valve stem is urged by spring 44 to a position closing the valve connecting the conduits 17 and 18. Discharge pressure through the conduit 15 into the opposing side of the diaphragm permits flow of regulating fluid. The amount of pressure in the conduit 15 necessary to open the valve may be predetermined by any usual means, such as adjusting the tension of the spring. The valve stem 41 is connected to a rack and pinion device 45 which, in turn, is connected to an indicating means 46 on the face of the means 16. Regulating fluid, when permitted to pass the regulating means 16, is conducted to a suction control means 19. The pressure of the regulating fluid in the conduit

2

18 is, of course, adjusted by the regulating means 16 which in turn is responsive to the discharge pressure from the compressor, as just described. A slow bleed 18a of any suitable sort is provided in the line 18, as is customary in such controls, to permit pressure to drop in the line 18 after the valve 40 has opened and closed during a control cycle. Also connected to the control means 19 is a source of control fluid under pressure conducted to the control means by the conduit 20. In the drawings, the control fluid and regulating fluid receive their pressure from a single source (not shown) through the conduit 21, however, it is clear that two separate sources of fluid under pressure may be provided, if desired. The control means 19 is constructed somewhat similarly to the regulating means 16, it being a device adapted to permit or prohibit control fluid pressure to enter the conduit 22. A suitable means is shown in Fig. 3 in which an air chamber diaphragm 47 is connected to a valve 48. Regulating fluid pressure in conduit 18 is admitted to one side of the diaphragm and suction pressure to the other side by means of conduit 34 connected to the intake 12. Spring means 49 normally maintain the valve operated by the diaphragm in a closed position, the tension of the spring being such that it is overcome by excessive differences between regulating fluid pressure and suction pressure to open the valve to permit control fluid to pass into the conduit 22. A rack and pinion device 50 is connected to the valve stem 51 and to an indicating means 52 on the face of the means 19. The control means is so adjusted that it will permit the control fluid to flow through it and, by means of the conduits 23 and 24, to the valve means 25 and 26. The valve means 25 is adapted to open or close a shutter 27 on the suction side of the compressor. A spring 28 normally maintains the valve 27 in closed position as shown, it being understood that the valve is provided with a few holes to permit refrigerant, or whatever gas is being compressed, to flow therethrough to the compressor even when the valve is fully closed. The pressure of the control fluid passing through the control means 19 and conduits 22 and 23 enters an air chamber 29 on one side of a diaphragm 30. When the pressure in the air chamber is sufficient to overcome the tension of the spring, the valve 27 will begin to open. In the normal refrigeration compressor, I prefer to have the valve 27 begin to open when the control pressure is in the neighborhood of 2 pounds, it being fully open when the pressure reaches approximately 10 pounds. Control pressure is also supplied by means of conduit 24 to the valve control means 26. This means is constructed to remain closed in normal operation, the valve 31 being held in such closed position by the spring 32. I prefer

to choose a spring having a greater resistance than the spring 28, to prevent the valve 31 from opening under lower pressures. In other words, if the first spring 28 is adapted to begin to open at a pressure of 2 pounds, and to be fully opened at a pressure of 10 pounds, I prefer to construct the spring 32 so that the valve 31 will remain fully closed until the pressure reaches 10 pounds, and the valve 31 will become fully opened when the pressure in the air chamber 33 reaches 18 pounds. It can be seen then that the valves 25 and 26 operate in sequence, the valve 25 being opened fully before the valve 26 begins to open. A slow bleed 22a of any suitable sort is provided in the conduit 22 so that when the valve 48 closes pressure may drop in the conduits 23 and 24 to permit valves 27 and 31 to return to their normal positions.

The operation of the device is as follows: the regulating means 16 is preset by the means hereinabove described to prevent regulating fluid from entering the conduit 18 until the discharge pressure has reached a desired minimum amount. As discharge pressure exceeds that amount, regulating fluid is admitted to conduit 18. The control means 19 is adapted to supply control fluid to the conduit 22 when the difference between the pressure of the regulating fluid and the pressure in the suction side of the compressor reaches a predetermined amount. It is evident, then, that the valve means 25 and 26 are called into operation only upon excessive pressure differences, and their control is independent of the actual pressures existing in the discharge conduit 11 or the suction conduit 12. The opening of the valve means 25 tends to increase the pressure on the suction side of the compressor. If the compression ratio continues to mount after the valve 27 is fully opened, additional control fluid pressure is admitted to the conduits 22 and 24, which additional pressure is sufficient to overcome the spring 32 and open the by-pass valve 31. Compressed gases are then by-passed directly to the suction side of the compressor, which immediately decreases the discharge pressure and increases the suction pressure to prevent surging. When pressure drops on the compression side, valve 40 is closed, and control fluid bleeds from the conduit 18 through the bleed 18a to reduce the pressure below the diaphragm 47 in the control unit 19, and at the same time the increased suction pressure raises the pressure above said diaphragm. As the pressure differential on the diaphragm 47 drops the valve 48 closes, and control fluid escapes through the bleed 22a to permit valves 27 and 31 to return to their normal position.

While I have shown and described my invention in its preferred embodiment, it is to be understood that it is capable of many modifications. Changes, therefore, in the construction and arrangement may be made without departing from the spirit and scope of the invention as disclosed in the appended claims.

I claim:

1. In a closed centrifugal compressor system including a compressor having a suction input and a pressure discharge, an anti-surge device comprising: a source of regulating fluid under pressure which is independent of the compressor system; regulating valve means; means connecting said valve means to said source of regulating fluid and to the compressor discharge whereby said valve means may pass regulating fluid at a pressure which varies within predetermined

limits with the discharge pressure; a source of control fluid under pressure; suction pressure control means connected thereto and to the suction input of the compressor and means interconnecting said valve means and said control means, whereby pressure of regulating fluid from said regulating means and pressure dependent on suction pressure jointly cooperate within said control means to allow same to pass control fluid at a pressure which varies directly with changes in the difference between the suction pressure and the pressure of the regulating fluid; and valve means mounted in the suction input and under the control of said suction pressure control means to vary suction pressure directly in response to variations in control fluid pressure.

2. The anti-surge device of claim 1, in which the valve means mounted in the suction input comprises a normally closed suction input valve which allows a predetermined minimum suction pressure when closed, said valve being adapted to be opened in response to pressure of the control fluid.

3. The anti-surge device of claim 1 and additional valve means including a normally closed by-pass valve operatively disposed in a conduit connecting the suction input with the pressure discharge and adapted to be opened in response to increasing pressure of the control fluid to by-pass gas from the discharge side of the compressor to the suction side thereof.

4. In a closed centrifugal compressor system including a compressor having a suction input and a pressure discharge, an anti-surge device comprising: a source of regulating fluid under pressure which is independent of the compressor system; regulating valve means; means connecting said valve means to said source of regulating fluid and to the compressor discharge whereby said valve means may pass regulating fluid at a pressure which varies within predetermined limits with the discharge pressure; a source of control fluid under pressure; suction pressure control means connected thereto and to the suction input of the compressor, and means interconnecting said valve means and said control means whereby pressure of regulating fluid from said regulating means and pressure dependent on suction pressure jointly cooperate within said control means to allow same to pass control fluid at a pressure which varies directly with changes in the difference between the suction pressure and the pressure of the regulating fluid; a first normally closed valve in the suction line of the compressor which allows a predetermined minimum suction pressure when closed; and a second normally closed valve operatively disposed in a conduit connecting the suction input with the pressure discharge, each of said valves being under the control of said suction pressure control means to open in response to increasing control fluid pressure.

ARNOLD H. HEINEMAN.
